OSCILLATABLE MINING MACHINE

Charles H. Record, deceased, late of Union, Oreg.,
by Mae Cook, administratrix, Union, Oreg.

Application February 8, 1939, Serial No. 255,248

4 Claims. (Cl. 209—446)

This invention relates to mining machines and has as one of its objects to provide a combined gravity concentrator and an amalgam separator that is simple in construction and assembly, and comparatively light in weight for transportation purposes, and that has increased capacity by increased rapidity of passage of the material therethrough.

Another object of the invention is to provide a mining machine that is adapted to be regulated to accommodate itself to substantially any of the precious metals or valuable minerals.

Another object of the invention is to provide a mining machine that may be adapted for use either manually or by any prime mover.

Another object of the invention is to provide a mining machine that is adapted for use to separate or concentrate, or both simultaneously and in one operation, from mineralized sand, from crushed ore, placer bed, or other source.

A further object of the invention is to provide a machine that is adapted to regulate the depth of the pulp on the separator by the adjustment of the angle thereof, in combination with the rate of feeding of the material, and movement imparted to said separator.

A further object of the invention is to provide a machine that is adapted to substantially continuous operation.

With these and other objects in view, reference is now had to the accompanying drawings in which

Fig. 1 is a plan view of the machine;

Fig. 2 is a side elevation thereof;

Fig. 3 is a longitudinal vertical section of a fragment of the machine;

Fig. 4 is a rear elevation of the head;

Fig. 5 is a perspective view of a fragment of the superstructure showing the frame of the amalgamating table, and its adjusting means;

Fig. 6 is a plan view of a representative discharge control;

Fig. 7 is a side elevation of the gate of said control;

Fig. 8 is a rear elevation of the control guide post;

Fig. 9 is a sectional elevation taken on the line 9—9 of Fig. 6;

Fig. 10 is a graph showing the result of a combined reciprocating and revolving motion elongating the minor axis of an ellipse at one end and shortening the minor axis at the other end; and

Fig. 11 is a side elevation of a fragment of a shaft and stub shaft showing collar in section.

Having reference to the drawings like numerals refer to like parts throughout the several views and the numeral 1 refers to a substructure, providing a supporting base which consists preferably of a table-like frame, preferably having a length in excess of its width, and constructed of any suitable material that will provide a firm support for a superstructure, to be presently explained, and that will withstand agitation of this superstructure both longitudinally and transversely from a direct revolving movement at one end thereof and diminishing to a reciprocating movement at the remaining end. And also that will support and sustain an operating mechanism 10 5 15 2 secured to the base at one end thereof, against rocking during operation of the machine.

The power to provide this movement may be either manual, in the lighter machines, or may be provided by any prime mover (not shown), 20 and as the work does not require a complicated mechanism, the simple mechanism shown in Fig. 2, and in section in Fig. 3, will suffice and may be explained as consisting of a vertically positioned shaft 3 journaled in bearings 4 secured to the cross pieces 5 of the base and on which is secured, in the customary manner (not shown), a drive wheel 6 connected to a prime mover (not shown) by the usual belt (not shown), while a fly wheel 7 will tend to counterbalance the action when placed as shown.

The shaft 3 terminates at its upper end in an eccentric of any approved type (or as shown in section in Fig. 3) where a stub shaft 8 is provided in continuation of the said shaft 3, and off center therewith, and on this stub shaft is mounted a sleeve 9 bored to seat on the stub shaft and likewise off center, whence by revolving the sleeve thereon and securing it to the stub shaft by a set screw 10, at any predetermined point, adjustment of the throw of an eccentric 11 may be accomplished, the sleeve 9 being adapted for engagement by a ball bearing, represented as at 12, secured rigidly to a superstructure 13 and thus providing, with the eccentric, an adjustable connection.

Obviously other means (not shown) may be used to provide an eccentric movement if desired.

The superstructure 13 consists of a rectangular head frame 14 constructed of any suitable material and provided with a head end 15 and a tailings end 16, and substantially of the same dimensions in plane as the substructure, and is supported for sliding action on rests secured to and 40 45 50 55 59 extended from the base 1, these rests positioned

at the head end of the base carrying the mechanism being termed transverse rests 17, being flat to accommodate the revolving motion of the head frame at this end (obviously a ball or other thrust bearing not shown may be utilized at this point to prevent friction), while rests adapted for reciprocating movement only, and being termed reciprocating rests 18, are provided at the tailings end 16 where the very slight revolving movement near this end is compensated for by the flexibility of the head frame 14.

Thus is mechanically provided a variable transverse movement gradually diminishing from one end to the other, thus simulating a hand panning movement where the maximum movement obtains at the point of beginning of the operation to provide a centrifugal force and the minimum movement obtains at the finish of the operation to spread the material.

When the eccentric 11 is assembled a removable cap 19 covers the eccentric and is secured thereon by a clip 20 which is pivotally secured to the head frame 14 and which is provided with an extended arm 21 disposed and adapted to secure the cap in place. By this means the eccentric 11 is made accessible for cleaning, oiling or adjustment of the throw.

The head end 15 of this head frame 14 is so called as a concentrator head 22 (to be explained), is positioned thereon, and forming a part of the superstructure 13 are vertical posts 23 secured rigidly to the head end of the head frame, at their lower end, and at their upper ends, carry a rectangular head-supporting-frame 24 which binds the four posts together wherewith to provide a support for the concentrator head 22, which will now be explained.

The concentrator head 22 is adapted to receive the material to be concentrated and for the purpose the material is reduced to a gange or pulp by the addition of water, preferably as it enters the head, whereby to facilitate handling, and comprises a plurality of superimposed pans, preferably of concave form and consisting of a lowermost overflow pan 25 supported on the head-supporting-frame 24 by braces 26 (shown in Fig. 3), and provided at its central and bottom portion with an orifice 27 providing an outlet therefrom for a purpose to be explained.

An uppermost head pan 28 is removably contained in and spaced concentrically with the overflow pan a distance to permit a free flow of pulp therebetween and these two pans are of a relative size to discharge from the head pan, over its perimeter or rim, in a thin veil, into the overflow pan without possibility of flow of the pulp over the edge 29 of said overflow pan.

A removable loosening baffle 30 is contained in and spaced apart from said head pan 28 and consists of a substantially circular plate concentrically positioned with respect to the head pan, and paralleling the bottom thereof, and is cut to provide upturned vanes 31 projected therefrom to provide means to maintain the flowing and porous condition of the passing pulp and permit the heavier values to pass thereunder, and this baffle and head pan are secured in their relative position with the overflow pan in a manner to be explained.

A feed funnel 32 is provided and is equipped at its lower end with a flat screen 33, positioned below the rim of the head pan, the screen being adapted to prevent the passage of any material too large to pass between the said baffle and head pan, and the head pan and overflow pan,

and said funnel is disposed to discharge onto said baffle, with a spreading action, and into said head pan, permitting the light sand to rise through the pulp and pass off, and loosening the heavier pulp to permit settling of the heavier particles.

Said funnel is hingedly attached to the head-supporting-frame 24 by means of a hinge member 34 secured thereto and carried outside of the superimposed pans and extended downward for rigid securing to the head-supporting-frame, while an oppositely positioned member 35 terminates in a washer-like end 36 to be secured to a bracket 37 by a thumb nut, represented as at 38, this last named member in turn being rigidly secured to said head-supporting-frame 24 in any suitable manner. By this means the funnel 32 may be released by the removal of the thumb nut and the funnel then removed, on its hinge, away from the center of the head pan and away from the baffle, should occasion require, for cleaning or other purposes, and hence makes for accessibility of the head pan and for removal of the concentrates which rest in the pocket 39 formed in the bottom of the said head pan and beneath the said baffle, this pocket constituting the first recovery point.

Directly beneath the overflow pan and disposed to receive from the discharge orifice 27 of the overflow pan is a pulp chute 40, upon which the pulp will drop, and which is secured integral with and between the said uprights 23 where it is positioned with a slight declination to discharge toward the tailings end 16 of the machine, and a bolt 41 is adapted to secure the baffle and head pan by passing therethrough and through the overflow pan to be secured by a thumb nut 42 beneath the said pulp chute.

The pulp chute consists of a lined box-like structure, the lining 43 forming the bottom of the chute, and terminating at substantially its low end in a transversely positioned cleanout channel or trough 44 having a removable wall 45 at its discharge end, the channel being disposed with relation to the said bottom of the chute that the pulp discharging from the bottom of said overflow pan will flow over and drop into the cleanout channel which will catch the heavier and valuable parts of the pulp remaining after passing the head pan, and thus provide a second recovery point, the pulp then dropping onto the discharge end 46 of the chute.

Upon flowing over this channel the pulp drops from the channel to a lower level of the lining 43 which is provided with a stop 47 passing part way across the discharge end 46 thereof, the open part remaining providing a discharge outlet 48 therefor.

To catch and further separate the precious minerals in the pulp a separator 49 is provided and disposed to receive the dropping pulp from the discharge outlet of the chute at its head and back, or high and diagonally positioned corner 50.

It may here be said that the head pan, overflow pan, pulp chute, and separator (to be explained) all may have their upper surfaces made active by being amalgamated in the manner well known in the art, where gold and silver, or like metals are to be recovered.

This separator 49 assembly consists of an auxiliary frame 51 hinged at its head end to the head frame 14 and is provided with a pair of oppositely disposed cam fingers 52 journaled in the head frame, at its tailings end, to raise or lower

this frame about its hinge point 53, whereby the level thereof, longitudinally may be adjusted.

Adjustment is made from the head, and during operation, by means of a remote control consisting of a rod 54 pivoted to the cam fingers 52 and terminating in a threaded end mounting (not shown), a hand wheel 55 is riveted to the rod, and the threaded end 56 is engaged in a threaded socket (not shown) preferably in the end cross piece 57 in the head frame in the usual manner. On the back side of this auxiliary frame 51 two straps 58—58, spaced apart, are secured, and on the front side at substantially each end of the auxiliary frame, are pivotally mounted discs 59, which by being pivoted off center provide two cams whose face is normally the same height as the aforementioned straps and which is provided with a like remote control operating both disc cams simultaneously through the medium of a connecting pitman rod 60, this rod being likewise extended rearward and threadedly engaged by a threaded member 61 secured to one of the uprights 23.

Secured rigidly to the straps 58 at the back edge and resting on the two circular cams at its front edge is the separator 49 proper, which consists likewise of a lined tray provided with an outlet 62 positioned diagonally opposite to the discharge spout 63 of the pulp chute 40, and providing a third point of recovery. This tray may be removable for substitution of other trays (not shown) if desired.

A gate 65 may be utilized to control the volume of discharge if desired and a typical gate is represented in plan in Fig. 6 and in side elevation in Fig. 7 where a tubular member 66 carries a blade 67 approximating one-half the opening in the tray, and the member 66 is provided with a spring clip 68 at one end to engage the edge of the tray 69 (see Fig. 9) and a post 70 (see Fig. 1) secures the remaining end of the gate against the thrust of the pulp.

The disc cams 59 are located on the front side of the table and when operated by their remote control the separator is adjusted transversely, the flexibility of the metal straps permitting such adjustment.

Obviously, hinges may be substituted for the straps if desired and springs, represented as at 64, on the front side may yieldingly secure the front side of the table in its proper relation with the disc cams 59.

The machine is designed to increase the efficiency of hand panning in recovering valuable minerals by utilizing the identical action of the hand pan on a large scale and preferably by power means, thus providing means to support and agitate the increased volume of material (over that of the hand pan) handled, and providing for uniform and continuous action as compared with the hand pan in which the first volume of ore handled must be completed before working a second and like volume.

In panning by hand the selected mineralized and barren materials are placed in the pan with water as above mentioned and the pan is then manipulated with an oscillating motion to agitate the contents to prevent the material packing, and the motion imparted to the pan for this purpose is variable depending on a combination of conditions, such as volume of material, as in the beginning of operation, and the specific gravity of the "values" to be recovered, and providing means to direct the movement of the concen-

trates to a suitable point of recovery, preferably toward the front edge of the separator.

Agitation of the hand pan is accomplished by grasping the pan with both hands and giving it a substantially circular motion at the beginning of the operation, to throw off the barren matter, and ending the operation by a substantially reciprocating motion of the pan to direct the movement of the concentrates to a suitable point in the pan (the juncture of the bottom and side) for the final recovery of the remaining concentrates.

This motion resolves itself into an elliptical motion accomplished by the use of the eccentric located at one end of the machine (the head end) which provides for a circular motion at the eccentric, and providing for a reciprocating motion at the other end, the combined motions describing an ellipse of varying minor axis in the agitated parts, obviously varying with the length of the superstructure, and providing a greater centrifugal action to the pans at one end of the machine, and a less centrifugal action at the separator end of the machine.

With this in mind the operation of the machine will now be explained:

The machine is set level, preferably adjacent to a running stream or other water supply, and as conveniently near to the material (which has previously been reduced to a sand by previous treatment) to be worked upon as possible, when the machine will be set in motion in the usual manner. This material, which has been screened by the proper mechanism to pass through the machine as above mentioned, is now deposited in the feed funnel by shovel or other available means, together with a regulated flow of water.

The water providing a flowing medium to the material, gravity causes it to pass through the funnel and its screen onto the baffle which will break up any tendency to pack, and as the feeding will be regulated the relatively large size of the funnel will provide a supply culminating in a steady flow of the material through the funnel and into the head pan.

The gradual influx of the material into the head pan, assisted by gravity, and centrifugal action caused by a short throw of the eccentric at a speed of approximately 200 R. P. M., now gradually moves the previously entered material toward the rim of the head pan which by its relatively large perimeter will keep the entire body of material in motion in a thin stream over its edge, assisting in the maintenance of its porosity and finally forcing the lighter material to discharge over the sides of the head pan and into the overflow pan and tend to return the precious minerals down its sloping sides and to the first recovery point.

With the surface of the head pan amalgamated, and made active thereby, and with a certain amount of quicksilver lying in the first recovery receptacle, in the bottom of this bowl-like concave head pan, and as the pulp is broken up at the baffle, gravity will cause the said quicksilver to permeate the flowing material to catch and add its weight to that of the particles susceptible of being caught by the quicksilver and thereby draw the saved matter under the baffle where it will not be further molested or affected by the moving material, to be recovered on removal of the said baffle.

As the overflow of barren matter from the head pan occurs the pulp falls into the overflow pan and passes over its active surface until it reaches the discharge orifice in its bottom to fall onto the

amalgamated plate of the pulp chute, which being inclined will assist gravity to move the pulp toward, into and over the cleanout channel where again any quicksilver laden matter escaping will fall into this channel to be subsequently recovered by removal of its removable discharge end.

The pulp after passing over the cleanout channel drops again onto a plane declining toward a discharge spout at the back side of the chute where it discharges by dropping onto the separator to be treated in a manner to be presently explained.

As before mentioned both the head, or concentrator end and the chute, are constructed as a unit with the head frame and hence the concentrator, being located nearest the eccentric will be provided with substantially a revolving or circular movement, in other words will describe an ellipse having a relatively greater minor axis while the tailings end will be provided with substantially a reciprocating movement and that the movement will vary from the one movement to the other throughout the length of the head frame, as shown plainly in the graph in Fig. 10.

Therefore with the greater agitation of the head the material will be kept looser to permit the mineral to fall by gravity to some lower point from which it can be recovered or its flow directed to that point.

It has now been shown that the heavier particles of the mineral will first be deposited in the head pan beneath the baffle, that the second point of deposit will be the cleanout channel, all under the influence of gravity assisted by the relatively circular agitation, and finally by means of the location of the separator and its relatively short transverse movement, augmented by gravity, and the gravity assisted by the adjustment of the table level, the minerals will be directed as indicated by the dotted streak, shown on the table in Fig. 1, representing the course across the table, to be recovered as a concentrate in any suitable manner, and providing a third recovery point.

Having thus described the invention, it is claimed:

1. In a mining machine of the character described, a concentrator comprising a frame, a superstructure carried by said frame, a feed funnel hingedly carried by said superstructure for movement into and out of an operating position over the same to receive material and water mixed to form a pulp, a concaved over-

flow pan carried by said superstructure and formed with an outlet at its center, a concaved head pan of less diameter than the overflow pan disposed in the overflow pan concentric thereto and spaced upwardly therefrom, a baffle in said head pan located centrally thereof and having upstanding radially extending vanes, the feed funnel when in an operative position being located over the baffle and the head pan concentric thereto, a chute carried by said superstructure under the overflow pan and formed with a transversely extending pocket intermediate its length and a discharge spout at one end, means at the foot end of the frame for guiding longitudinal reciprocating motion thereof, and means at the head end of the frame for imparting horizontal revolving movement to the frame while the foot end reciprocates longitudinally.

2. The structure of claim 1 wherein the chute extends longitudinally under the overflow pan at a downward incline toward its discharge end, the pocket consisting of a trough extending transversely across the chute in spaced relation to the discharge end of the chute.

3. The structure of claim 1 wherein the chute extends longitudinally under the overflow pan at a downward incline toward its discharge end, the pocket consisting of a trough extending transversely across the chute in spaced relation to the discharge end of the chute, and the portion of the chute between the trough and the discharge for the chute being stepped downwardly to provide a transversely extending shoulder across its inner end.

4. In a mining machine, a concentrator including a feeder, a plurality of concentric concaved pans therebelow, arranged one above the other in spaced relation and increasing in diameter downwardly, a baffle at the center of the upper pan having upstanding radial vanes, the lowermost pan having a central outlet therein, and a chute below said pans for receiving material therefrom formed with a collecting pocket, a support for said concentrator movable in a horizontal plane, means for imparting revolving movement to the concentrator-supporting end of the support in a horizontal plane, and means for guiding the opposite end of said support to restrict it to longitudinal reciprocating movement as the first mentioned end of the support revolves.

MAE COOK,
*Administratrix of the Estate of Charles H.
Record, Deceased.*
